UNITED STATES PATENT OFFICE.

LEWIS FERRY MOODY, OF PHILADELPHIA, PENNSYLVANIA.

HYDRAULIC VALVE.

Application filed December 30, 1925. Serial No. 78,422.

This invention relates to valve mechanisms, and more particularly an improved arrangement of valve parts and means for operating the same.

5 It is an object of my invention to provide a valve involving features which permit the valve to be of minimum outside diameter and reduced size of structure, and consequently of economical cost to manufacture.

10 It is a further object to provide such features that an improved method of valve operation and control may be had. Still another object of my invention is to provide an improved arrangement between a hollow plunger

15 valve and improved piston and cylinder elements for operating and controlling the plunger valve. A further object is to provide improved means for controlling the plunger valve in either direction of movement. A

20 more specific object is to provide improved means for preventing quick closure of the valve on approaching its seat, thereby avoiding water hammer. A further specific object is to control the plunger valve operation by regulating discharge of fluid from a space having a substantially leak-proof piston. Another object in this regard is to provide improved means for securely regulating the discharging fluid.

25 30 Other objects of my invention will appear from the following description of the accompanying drawings, in which

Fig. 1 is a longitudinal sectional view of the valve mechanism;

35 Fig. 2 is a modified form of the valve mechanism.

In the illustrative embodiment of my invention, I have shown an outer housing 1 interposed between up and downstream pipes 2 and 3. A combined chamber-forming and plunger guide member 4 disposed within the housing 1 slidably supports a plunger valve 5 by a rearwardly extending annular portion 6. A plunger valve seat 7

40 45 formed in the front end of the housing 1 is engaged by the plunger nosepiece 5^a which is removably secured to the portion 6. A removable point 5^b permits removal of a piston rod nut 9^a. A piston 8 connected to

50 the plunger valve by a rod 9 is disposed

within a cylinder 10, which is a part of the member 4. The front end of the cylinder is closed by a head 11 through which the rod 9 passes while the rear cylinder end has substantially free communication as by 55 passages 12 with the hollow plunger chamber A. A small counter-bore 13 is provided at the front end of the cylinder. The member 4 is provided with a removable cylindrical end 4^a to permit rearward removal of piston 8 besides other advantages. The piston 8 may be provided with suitable packing, or usual types of snap rings to effect as nearly a leak-proof piston as possible.

To control the plunger a passage 14 communicates at one end with a port 15 which is spaced from the cylinder head 11 and has communication with the counter-bore 13 while the other end of said passage is adapted to communicate with the passage 16 60 formed in the four-way valve 17. The passage 16 communicates with the upstream pipe 2 as by passage 18. A pipe 19 communicates at one end with the rear end of cylinder 10 and chamber A while the other 65 end of said pipe communicates with a passage 20 formed in valve 17. A drain pipe 21 is adapted to communicate at one end with the passage 20 while the other end may communicate with any suitable source of low 70 pressure such as the atmosphere or with the downstream pipe 3. If desired a closure 75 valve may be disposed in line 21.

To drain the cylinder 10, chamber A, and housing 1, there is provided valve controlled drain pipes 24, 25 and 26 communicating 80 respectively therewith and having communication with a common drain pipe 27. This drainage system does not enter into the normal operation of my device.

85 90 In operation of this form of my device, to maintain the plunger valve in or move the same toward open position, the valve 17 will be set as shown, in which case line pressure from pipe 2 will be transmitted to the front end of cylinder 10, while the chamber A which includes the rear end of cylinder 10 will have communication with a lower source 95 of pressure, such as the atmosphere or downstream pipe 3. To close the plunger 100

valve, valve 17 will be rotated through 90° to place the front cylinder end in communication with the low pressure source and to place the chamber A in communication with a high pressure source, such as the pipe line 5. When the valve approaches the seat 7, the piston 8 will overrun the port 15, as shown in dotted lines, after which any fluid discharged from the cylinder will be by way 10 of the restricted passage formed by the counter-bore 13, thereby positively retarding plunger movement and preventing the same from slamming. If desired to stop the plunger in mid-position, the valve 17 may be 15 turned through 45°, thereby preventing the discharge or admission of fluid to the front end of cylinder 10, and due to the piston and cylinder having substantially leak-proof fit the plunger will be held stationary. 20 In the modified form shown in Fig. 2, the housing 30 encloses a combined chamber-forming and plunger guide 31, which slidably supports a plunger valve 32 as by an annular portion 33. A piston rod 34 secured 25 at its rear end to the member 31 carries a stationary piston 35 which is disposed within a cylinder 36 carried by and forming a part of the annular portion 33. The front end of cylinder 36 is open to chamber A' 30 while the rear end is closed by head 37, through which the rod 34 extends. To control plunger movement, a passage 38 formed in rod 34 communicates at one end with radial ports 39 adjacent an annular reduced 35 portion 40 while the other end of the passage 38 communicates with a pipe 41. A four-way valve 42 has a passage 43 adapted to communicate with the pipe 41, and with a drain pipe 44, which can be connected to 40 the atmosphere or downstream pipe. The chamber A' consisting of the hollow portion of the plunger and the front open end of cylinder 36 is adapted to have communication with a pipe 48 through valve passage 49. The plunger is provided with a removable nosepiece 50 which engages a seat 51. A point 52 is removably secured to piece 50 to permit forward removal of piston 35, aside from other advantages. 45 Valve controlled drainage pipes 53, 54 and 55 are adapted to have communication respectively with the rear cylinder end, chamber A', and housing 30.

The operation of this form of my invention is substantially the same as in the other form except that the cylinder 36 moves with the plunger 32, and when the latter approaches closing position the cylinder head 37 will overrun the radial ports 39, thereby 55 retarding plunger movement by causing discharge of fluid from the cylinder through the restricted annular passage 40.

The two forms disclosed have certain common characteristics, such as the provision of 60 a hollow plunger, and piston and cylinder

elements, so arranged as to provide only two chambers. Also means are provided for positively controlling plunger movement at one end of the plunger stroke, and the plungers may be positively controlled 70 throughout their operation by regulating the discharge of fluid from a single space having a substantially tightly fitting piston.

Among the advantages of this valve may be mentioned the fact that in closing the 75 full pressure in the upstream pipe may be admitted to the entire inside surface of the downstream end of the plunger, which will result in a force sufficient to close the valve even against the reaction of the water when 80 freely discharging under full head, as in case of a rupture of the downstream conduit below the valve. At the same time the plunger motion in closing may be effectually controlled or stopped by throttling or shutting 85 off the discharge of fluid from a tightly packed cylinder thus insuring that the entrapped, incompressible fluid will automatically adjust its pressure to whatever 90 value is necessary to hold the plunger, rather than by depending solely upon the reduction of the operating pressure which is tending to move the plunger toward closed position, or by attempting to equalize the 95 pressures acting on the face of the plunger. 100 In providing a chamber in which fluid can be entrapped for this purpose of control, reliance is not placed on the use of small clearances around the outside of the plunger itself, since these clearances must in practice be made liberal from practical considerations, but as explained this chamber is provided by an internal cylinder of reduced diameter adapted to form a close fit with a piston carried by a piston rod. 105

I claim:

1. A valve mechanism comprising inner and outer casing spaced to form a smooth annular fluid passageway, a plunger having telescopic relation with said inner casing to form an internal fluid chamber, a cylinder carried by, but spaced inwardly from said plunger, a piston disposed within said cylinder and a piston rod connecting said piston and said inner casing, said cylinder having its upstream end closed while its downstream end is open to said internal chamber. 110

2. The combination as set forth in claim 1 further characterized by having the forward end of the plunger entirely closed. 115

3. A valve mechanism comprising cooperative casing and plunger members having an operating chamber associated therewith, piston and cylinder elements spaced from but operatively connected to said plunger for controlling the same, a piston rod connecting said piston and one of said members, means for closing one end of said cylinder, while the other end has substantially free communication with said operating chamber, 120

thereby to form only two fluid chambers, and means within said cylinder for cushioning movement of said plunger near one end of its stroke including a passage within said 5 rod.

4. A valve mechanism comprising a plunger having a closed forward end, piston and cylinder elements for controlling the same, a piston rod, means including a passage extending through said rod whereby fluid may substantially freely flow from one end of said cylinder, and means whereby fluid flow from the other end of said cylinder is adapted to be exhausted.

15 5. A valve mechanism comprising cooperating casing and plunger members forming a chamber, piston and cylinder elements for controlling said plunger, means whereby fluid may substantially freely flow between 20 the downstream end of said cylinder and said chamber, and means including a groove formed in one of said elements whereby fluid flow from the other end of said cylinder is automatically restricted upon predetermined 25 relative movement between the piston and cylinder elements.

6. A valve mechanism comprising cooperating casing and plunger members forming a chamber, piston and cylinder elements 30 for controlling said plunger, means whereby fluid may substantially freely flow between the downstream end of said cylinder and said chamber, and means whereby fluid flow from the other end of said cylinder is automatically 35 restricted upon predetermined relative movement between the piston and cylinder elements, said restriction means including a port adapted to be substantially covered by the piston and a restricted passage which is 40 operative after port covering.

7. A valve mechanism comprising a plunger having an inner pressure receiving surface, means forming a chamber bounded by said surface, piston and cylinder elements for 45 controlling said plunger, said cylinder being spaced from and operatively connected to said plunger, a piston rod, means for controlling the admission and discharge of operating fluid to and from both said chamber and 50 said cylinder, and a passage in said rod for controlling fluid to one end of said cylinder.

8. A valve mechanism comprising a plunger having an inner pressure receiving surface, means forming a chamber bounded by 55 said surface, piston and cylinder elements for controlling said plunger, said cylinder being spaced from and operatively connected to said plunger, a piston rod, means for simultaneously controlling the admission and 60 discharge of operating fluid to and from both said chamber and said cylinder, and a passage in said rod for controlling fluid to one end of said cylinder.

9. A valve mechanism comprising a plunger, piston and cylinder elements for control-

ling the same, a rod for holding said piston and means whereby fluid flow from one end of said cylinder is automatically restricted upon predetermined relative movement between the piston and cylinder elements, said 70 restricting means including a port adapted to be substantially covered by the piston and a restricted passage formed on the outside of said rod and rendered operative after port covering.

CERTIFICATE OF CORRECTION.

Patent No. 1,727,517.

Granted September 10, 1929, to

LEWIS FERRY MOODY.

It is hereby certified that error appears in the printed specification of the above numbered patent requiring correction as follows: Page 3, lines 9 and 10, claim 4, strike out the words "including a passage extending through said rod" and insert the same to follow after the word "means" line 12, same claim; and that the said Letters Patent should be read with this correction therein that the same may conform to the record of the case in the Patent Office.

Signed and sealed this 29th day of October, A. D. 1929.

M. J. Moore,
Acting Commissioner of Patents.
